UNITED STATES PATENT OFFICE.

ARTHUR JAMES MASKREY, OF MARTINS FERRY, OHIO.

FEEDING MECHANISM FOR BRANNERS.

SPECIFICATION forming part of Letters Patent No. 740,294, dated September 29, 1903.

Application filed October 30, 1902. Serial No. 129,393. (No model.)

To all whom it may concern:

Be it known that I, ARTHUR JAMES MASKREY, a subject of the King of Great Britain, and a resident of Martins Ferry, county of 5 Belmont, and State of Ohio, have invented certain new and useful Improvements in Feeding Mechanism for Branners, of which the following is a specification.

My invention relates to new and useful improvements in feeding mechanism for branners, and more particularly to a device for automatically feeding sheets of metal or metal plates to branners.

The object of my invention is to provide a 15 simple device of the character mentioned which co-operates with an automatic catcher shown and described in my application for patent therefor, which application is filed simultaneously herewith and reference to which 20 is herein made.

A further object of my invention is to provide a device for feeding metal plates to branners which will feed the plates singly, no matter at what rate of speed the said plates are 25 being delivered thereto, and which consequently obviates the formation of cobbles which is consequent to the feeding of more than one sheet or plate at a time.

With these and other objects in view my invention finally consists in the particular construction, arrangement, and combination of parts, which will hereinafter be fully described, reference being herein had to the accompanying drawings, forming a part of this 35 specification, in which—

Figure 1 is a side elevation of my invention, showing tipping cradles mounted thereon. Fig. 2 is a top plan view of the same. Fig. 3 is a front edge view of a cradle.

Referring to the drawings, in which like reference-numerals designate like parts throughout the several views, 1 indicates the front end of the branner, 2 the forward extensions or side rails thereof, 3 the carrying-forks, 4 the cross-bars on which the forks are mounted, 5 the fork-carrying chains, 6 a shaft journaled in the side rails 2, and 7 the wheels on the shaft 6 for carrying the chains 5, all of the above being of the usual present construction.

To the front end of each side rail 2 I secure one end of a substantially U-shaped bar 8,

which extends from one side rail 2 to the other, as shown. Supported at their front ends by the cross-bar 8 and at their rear ends by a cross-bar 9, which extends from one side to the other, are a plurality of parallel inclined bars 11, having smooth upper surfaces forming a table. Said table is supported at the rear end by supports 10, of sufficient length to hold the table at a suitable angle for permitting metal plates to slide forward thereon by their own weight.

Adjustably mounted in slots 12 in the bar 8 and in slots 13 in the bar 9 at each side of the table are vertical posts 14. Supported by said posts 14 at each side of the table is a side guide 15, said guides being adapted for guiding a sheet of metal forward on said bars 11. Said posts 14 are substantially L-shaped, as shown, and have passing therethrough and through the slots 12 and 13, respectively, bolts 35, with nuts on their lower ends by which said posts are secured in place in said slots. When said nuts are loosened, 75 the side guides 15, which are supported by said posts, may be adjusted to regulate the distance therebetween to accommodate different-sized sheets of metal. Suitably journaled in the rear ends of said side guides 15 are the ends of a shaft 16, on which is mounted a tipping cradle 17, and suitably journaled in supports 18, provided on the guides 15, is the shaft 16 of a second tipping cradle 17. The construction of said cradles will presently be 80 shown.

Pivoted at 34 to the side rail 2, at one side of the front end of the branner 1, is a bar or rod 19, the front end or point 20 of which extends forward into the front end of the branner and is normally balanced and held in the position shown in Fig. 1. The rear end of said rod 19 extends backward from the pivot or fulcrum 34, thence crosses to the opposite side of the front end of the branner underneath the bars 11, and thence extends forward and is pivoted at 21 to the side 2 opposite the fulcrum 34. Secured to that portion of the rod which passes across underneath the bars 11 are a plurality of upwardly-extending arms or stops 22, located at points between the bars 11, which normally project upward between said bars 11, so as to prevent a sheet of metal from sliding into the

hooked ends 23 of said bars 11. The front end or point 20 of the bar 19 is provided with a substantially U-shaped bend, as shown in Fig. 1, the object of which will presently be 5 shown.

At the end of each shaft 16 of the tipping cradles is provided a keyed arm 24, which extends forward horizontally when said cradle is in its normal horizontal position. Said

10 arm is connected by rope, chain, or other suitable device 25 through a pulley 26, stationed on the floor or other suitable position, with a weight 27, said weight being the balance-weight shown and described in my application for patent for automatic catcher hereinbefore referred to.

The cradles shown are specially adapted for receiving metal plates from my said automatic catcher when the said catcher is located 20 at the end of the tinning-pot, since said sheets

25 are then delivered sidewise. Said cradle consists of a plate 36, mounted upon the shaft 16, and is provided with a flat horizontal surface 37 and with an inclined surface 28, substan-

30 tially as shown in Fig. 3. Said inclined surface 28 is provided on the end of the cradle next the automatic catcher, the object there- of being to cause the lower edge of a sheet of metal dropped thereon to slide backward, so

35 as to throw the upper end of the sheet forward along said cradle. When a metal plate is dropped on said cradle from the arm of my automatic catcher hereinbefore referred to, said arm begins to return. This action raises

40 the weight 27, which is suspended therefrom, and consequently the arm 24 is drawn downward, tipping the cradle forward, so as to permit the plate to slide forward to the bars 11. The plate so tipped will slide forward against

45 the stops 22, where it will be held until the bar 4, on which the forks 3 are mounted, rises between the side rails 2 of the branner. Said bar 4 in turning over the shaft 6 raises the point 20 of the bar 19, and the bend of said

50 point causes it to be raised still farther as the bar 4 passes thereunder. As is obvious, when the point 20 of the rod 19 is thus raised the rear end thereof carrying the stops 22 will be lowered until said stops are below the bars

55 11, permitting a metal plate resting therebehind to slide forward into the hooked ends 23 in position to be engaged by the next set of forks 3. When the bar 4 passes from under the bar or rod 19, said rod drops back to its

60 normal position, raising the stops 22, so as to prevent the next metal plate from sliding into the hooks 23 until the first has been carried forward. The forks 3 are located but a short distance apart in order that a sheet delivered

65 to the hooks 23 will almost immediately be grasped and carried forward.

As is obvious, when but one arm is used on the main shaft of the automatic catcher hereinbefore referred to but one tipping cradle

65 17 is necessary; but when two or more arms are used an equal number of cradles located

beneath the respective delivery positions of the arms are required.

Since the metal plates are fed into the tinning-pot so that the arms of the automatic 70 catcher operate and deliver said plates alternately, said cradles are tipped alternately, and consequently but one sheet of metal is permitted to slide forward to the bars 11 at a time.

Provided on the side of the table opposite the side from which the sheets are delivered thereto is a vertical plate or stop 33 for preventing sheets of metal from being thrown over the table.

As will be seen by reference to the application for patent for automatic catcher hereinbefore referred to, when the carrying-arm of the said catcher lies in its normal position the balance-weight thereof is held in a raised position, which position holds the cradle of the present device tipped. Immediately, however, when the said arm begins to rise or turn back said cradle, which is heavier at the rear side than at the front, begins to turn back to 90 a horizontal position ready to receive the sheet being delivered thereto from the said arm.

The hooks 23 are formed with an acute angle at the end of the straight portion of the 95 rods 11, the points of said rods bending gradually upward and backward from said angle. The object of this construction is to form hooks against which the sheets in sliding forward strike glancingly, thus preventing the 100 bruising of the edge of the sheet which is consequent when said edge strikes directly against a bar standing at right angles thereto.

Having thus described my invention, what I claim as new, and desire to secure by Letters 105 Patent, is—

1. In a machine of the character described, the combination with a branner and its sheet-carrying mechanism and with the balance-weights of an automatic catching apparatus, 110 of a plurality of parallel bars mounted at their front ends in front of said branner and suitably supported at their rear ends, the front ends of said bars forming hooks for holding a sheet of metal in position for being 115 grasped by the sheet-carrying forks of the branner, a guide adjustably mounted at each side of said parallel bars, a shaft journaled in supports and supported above said parallel bars, a cradle mounted on said shaft over 120 said parallel bars, an arm secured on one end of said shaft, a rope or chain connecting the end of said arm, through a suitably-located pulley, with the said balance-weight, whereby when said balance-weight rises the 125 point of said arm is drawn downward tipping the cradle forward, a rod pivoted in one side of the front end of the branner and having its front end extending forward into the branner and its rear end crossing transversely 130 underneath the parallel bars and pivoted in a suitable support, vertical stops provided on

the transverse portion of said rod between the parallel bars, and means whereby said rod, bearing said stops, is tipped downward, substantially as described.

- 5 2. In a machine of the character described, the combination with a branner, the sheet-carrying mechanism thereof, and with the balance-weights of a machine for catching sheets of metal as they rise from the rolls of 10 a tinning-pot, of an inclined table having its front end mounted on the front end of the branner; said table comprising a plurality of parallel inclined bars having their front ends formed into hooks in the path of the sheet-carrying forks of the branner; an adjustable guide at each side of said table; tipping cradles mounted on said table under the respective delivery-points of the catching-machine; arms on the ends of the shafts of said tipping cradles; connecting means suitably arranged between said arms and the said balance-weights whereby when said weights are raised said cradles are tipped; a rod pivoted to the front end of the branner and passing 25 transversely underneath the parallel inclined bars of the table; vertical stops on said rod which normally project upward between said parallel inclined bars; an integral arm carried by said rod, the front end of which extends forward into the front end of the branner, whereby when the cross-bar, carrying the forks of the branner, rises thereunder said stops are lowered beneath the said parallel inclined bars, substantially as described.
- 30 3. In a machine of the character described, the combination with the sheet-carrying mechanism of a branner, and with the balance-weights of a machine for catching metal plates as they rise from the rolls of a tinning-pot, 35 of an inclined table having its front end mounted in front of said sheet-carrying mechanism of the branner, sheet-holding hooks provided at the front end of said table in a

position in the path of the sheet-carrying forks; tipping cradles mounted above said table, means attached to said cradles whereby said cradles are tipped by said balance-weights, a pivoted rod passing transversely underneath said table, stops provided on said rod which normally project upward through 50 said table, and means whereby said stops are withdrawn from said table at intervals, substantially as and for the purposes set forth and described.

4. In a machine of the character described, 55 the combination with the sheet-carrying mechanism of the branner, and with the balance-weights of a machine for catching metal plates as they rise from the rolls of a tinning-pot, of an inclined table having its front end mounted in front of the branner, hooks provided in front of said table for holding a sheet of metal, said hooks being located substantially in the path of the sheet-carrying forks of the branner; tipping cradles mounted above said table, means carried by said cradles whereby said cradles are tipped by said balance-weights, means whereby a sheet of metal delivered to said table is prevented from sliding into said hooks until any other sheet held 65 by said hooks has been removed therefrom, substantially as described.

5. The combination, in a device of the character described, with the sheet-carrying mechanism of a branner, of a table secured to the 70 front end of a branner, and means carried by said table and the branner mechanism whereby said mechanism controls the delivery of a sheet of metal thereto, substantially as described.

Signed by me at Wheeling, West Virginia, this 24th day of October, 1902.

ARTHUR JAMES MASKREY.
